UNITED STATES PATENT OFFICE.

FRANK B. McMAHON, OF NEW YORK, N. Y.

STATIONARY NON-BRUSH DEVICE FOR WOOL-COMBERS.

1,156,912.

Specification of Letters Patent. Patented Oct. 19, 1915.

Application filed July 20, 1915. Serial No. 40,994.

To all whom it may concern:

Be it known that I, FRANK B. McMAHON, a citizen of the United States, and a resident of the city of New York, borough of Brooklyn, in the county of Kings and State of New York, have invented a new and useful Improvement in Stationary Non-Brush Devices for Wool-Combers, of which the following is a specification.

10 This invention relates to an improvement in a stationary, non-brush device adapted to press wool into the needles of a circle combing machine such as is used in the combing of wool.

15 One of the objects of the invention is to do away with the dabbing brush and dabbing motion such as is used on wool combing machines of this character, which attachments are, as well known, generally ex-

20 pensive to keep in repair and somewhat complicated and difficult to adjust, and substitute therefor a device which is simple, easily adjusted, and which will wear indefinitely.

25 A further object of the invention is to eliminate entirely the use of power in driving a dabbing motion, and substitute therefor a device that will hold the wool into the needles of the combing machine, but which device does not have to be driven by means

30 of power.

Another object of the invention is to avoid the uneven wearing of a bristle brush generally used on wool combing machines, and the consequent uneven work thereby pro-

35 duced and substitute a stationary, metal device that will not wear uneven in certain parts but which will at all times operate evenly on the wool, consequently making an even sliver coming from each side of the 40 comb, thereby securing better and more uniform work from the machine, besides increasing the quantity of production.

Further objects of the invention are to provide a simple method of quickly adjusting 45 the device on the combing machine, and quickly disconnecting it from the machine, for means of repairing other parts of the combing machine whenever necessary, and to provide a method of holding the blades in

50 a pre-determined position centrally between the rows of needles or pins so that the blade cannot in any way injure the pins by shifting its position, but whenever an extra end or piece of wool goes under the blades, the 55 blade or blades are caused thereby to oscillate vertically only, so that injury to or

breaking of the pins in the circle is avoided. In the same way whenever the machine gets clogged or any foreign matter lodges in the circles, the extra matter raises the blade or blades on the pistons and after the foreign matter has passed under, the blade or blades return to their original positions. The blade or blades, therefore, adjust themselves automatically to any thickness of the wool, 60 or indeed to any foreign matter presented to the blade or blades.

In the accompanying drawings, which are to be taken as part of this specification and in which I have shown a preferred form of 70 the invention—

Figure 1 represents a top plan view of the device attached to the circle column and showing the dotted lines indicating the rows of needles or pins in the comb circles. Fig. 75 2 represents a front view of the entire device, Fig. 3 represents a detail view, partly in section, showing one of the pistons holding the blades. Fig. 4 represents one of the several radial arms, detached; and shows the 80 chamber for the pistons just referred to.

The same reference characters indicate the same parts in all the figures.

Referring to the numerals on the drawings there is shown and the invention consists of a supporting plate 1, supporting a plurality of adjustable radial arms 2, which parts will be called the holder, and a plurality of narrow blades 3, which are attached to the pistons 4 and held in proper position 85 by the holder 2. The holder and blades together are so attached to the column 5 of the combing machine as to press the wool down into the pins of the comb circles with that degree of tension required by the work 90 to be done. This tension is regulated by the spring 6, in connection with the adjustable collar 14 and the piston 4. The dotted lines 7, indicate the rows of pins or needles on the comb circles, and between which rows of 95 pins the blades 3 are adjusted to a pre-determined position.

The supporting plate 1 has a slot 8 by which the holder and blades are adjusted to the pins, after which the plate is bolted to the column 5 by the bolt 9, binding on the washer 10, and further secured from shifting by the two set screws 11.

Each of the several radial arms 2, known as the holders, are rigidly fastened to the 110 supporting plate 1 by bolts 12 through a slot, for means of adjustment, and the radial

arms are of such suitable lengths as to position the piston chambers 13 so that each of the blades 3 attached to the pistons 4 are centrally located between the rows of needles 7. The construction and arrangement of the blades and the radial arms may vary somewhat according to whether fine work or coarse work is being run on the comb, but in coarse work the arrangement of the radial arms, piston chambers, pistons, and the blades are preferably as shown in the drawing.

Each of the several radial arms contains as many pistons as is necessary to hold each 15 of the blades by a plurality of pivot joints 17 located at the top of the blades. The piston chambers 13 are formed by boring holes in the holders or radial arms 2, and through these holes or chambers the pistons 4 are passed. The top of the piston is secured by a collar 14, which has one or more sides round and the other opposite sides 20 straight, and the position of the piston, and consequently the blades, is adjusted to any 25 pre-determined position by means of a set screw 15 passing through the collar 14 to the piston 4, and a set pin 18, usually located opposite the set screws on the collar and set into the chamber walls, as shown in detail in Fig. 3. By this method of fastening, the piston, and consequently the blades, cannot turn, but can move only up and down in the chamber. The opposite end of the piston 30 4 is finished in a square shoulder 16, slotted 35 to receive the blade 3, which is fastened by a pivot 17, thereby making a pivot joint between the blades and the piston. Moreover a spiral spring 6, is placed upon the lower end of the piston 4, bearing between the 40 bottom of the holder 2 and the shoulder 16 on the end of the piston 4, as is shown in Fig. 3.

The method of operating the device is by adjusting the tension of the spiral spring 6 45 by means of the movable collar 14 on the piston 4. This determines the degree of tension required to be exerted by the blades 3, which have been first adjusted to the proper position centrally between the rows of pins. When properly adjusted the bolts are tightened and the blades are held in this pre-determined position. No power is used to drive the device; the tension or pressure 50 upon the wool being supplied by the proper positioning and adjustment of the entire device together with the adjustment of the collar on the piston and the tension of the spring. As the hank of wool approaches the nose of the blade 3^a, it is gradually and

gently pressed down under the center of the 60 blades where an even and gentle pressure is maintained by the blades while the wool is being combed by the tangent circles of pins or needles. This action of the device allows 65 the wool, after passing a certain point, to gradually come up to the top of the needles after being combed, giving the drawing aprons a nice, free end to draw, which is an improvement over the old dabbing brush and the various devices for jabbing or compressing the wool far down into the needles. 70

Having thus described the invention, I claim as new and desire to secure by Letters Patent,

1. In a device of the kind described, a 75 supporting plate, having a slot therein for means of adjustment, attached to the column of a wool combing machine, a plurality of radial arms or holders, slotted for means of adjustment, and attached rigidly to the 80 said supporting plate, a plurality of pistons passing through chambers in said holders and attached to narrow blades by slotted shoulders and pivot joints, a plurality of narrow blades attached to and held in 85 proper positions centrally between the rows of pins, a collar containing a set screw and a set pin, for means of adjustment, at one end of said pistons, a spring on the ends of the pistons, for the purpose of yielding and 90 for acting upon the piston to bring it back to its original position when it becomes displaced, the construction of the holder and the arrangement of the radial arms and pistons being adapted to prevent any side or 95 radial motion of the blades, thereby protecting the pins on the circles from harm.

2. In a wool combing machine, the combination of a supporting plate, a plurality of radial arms or holders secured rigidly to 100 the said supporting plate, a plurality of pistons held in position by said radial arms or holders, a plurality of blades attached to said pistons by a plurality of pivot joints, a 105 spring attached to said pistons causing them to yield and to return to their original positions, thereby causing the wool to be pressed gently into the needles of the comb and to prevent any harm to the needles or machine should the machine become clogged or 110 should a foreign substance get into the circles, all substantially as described.

In testimony whereof I have affixed my signature in the presence of two witnesses.

FRANK B. McMAHON.
